(57) **CLAIM**

I claim the ornamental design for a silverware stand, as shown and described.

DESCRIPTION

FIG. 1 is a perspective view of a silverware stand, showing my new design in an assembled configuration;
 FIG. 2 is a front elevational view of FIG. 1;
 FIG. 3 is a rear elevational view of FIG. 1;
 FIG. 4 is a right-side elevational view of FIG. 1, the left-side elevational view being a mirror image thereof;
 FIG. 5 is a top plan view of FIG. 1;
 FIG. 6 is a bottom plan view of FIG. 1; and,
 FIG. 7 is a top plan view thereof, illustrated in a flat configuration.
 The broken lines showing utensils in FIG. 1 depict environmental matter and form no part of the claimed design.
